Primary Examiner—Jeffrey D Asch*Assistant Examiner*—Bridget L Eland(74) *Attorney, Agent, or Firm*—Michael Best & Friedrich
LLP(57) **CLAIM**

We claim the ornamental design for a compartmented tray, as shown and described.

DESCRIPTION

FIG. 1 is a perspective view of a compartmented tray embodying the present invention.

FIG. 2 is a top view of the compartmented tray shown in FIG. 1.

FIG. 3 is a front view of the compartmented tray shown in FIG. 1, the rear view being a mirror image thereof.

FIG. 4 is a bottom view of the compartmented tray shown in FIG. 1; and,

FIG. 5 is a left side view of the compartmented tray shown in FIG. 1, the right side view being a mirror image thereof.
